COMBINATION BAGGAGE RACK AND LIGHT-
ING FIXTURE

Carl H. Larson, Elkhart, Ind., John L. Mohun,
Chicago, Ill., and Christian M. Verhagen, Elkhart, Ind., assignors to The Adlake Company, Elkhart, Ind., a corporation of Illinois

Application April 13, 1936, Serial No. 74,004

11 Claims. (Cl. 224—29.5)

This invention relates to baggage racks for rail-way cars, busses, and the like, and some of the more important objects of the invention are as follows: To provide a rack which is made up of 5 readily assembled units; to combine a lighting fixture with the rack in such a manner that not only is proper lighting effected, but the appearance of the rack as a whole is greatly improved; to provide means for obtaining access to the lighting fixture without completely disassembling the rack; and to construct the wall bracket and rack unit in such a way that slight variances in the 10 positioning of the bracket are accommodated without being apparent to persons within the 15 car.

Further and other objects and advantages will become apparent as the disclosure proceeds and the description is read in conjunction with the accompanying drawings, in which

20 Fig. 1 is a perspective view showing a preferred embodiment of the invention;

Fig. 2 is a vertical, transverse, sectional view taken on the line 2—2 of Fig. 4;

25 Fig. 3 is a longitudinal, horizontal, sectional view taken on the line 3—3 of Fig. 4;

Fig. 4 is a longitudinal, vertical, sectional view taken on the line 4—4 of Fig. 3;

Fig. 5 is a perspective view of the wall bracket with the cover lifted and parts broken away to 30 expose the interior of the bracket;

Fig. 6 is a perspective view of the rack unit; and

Fig. 7 is a perspective view of the end bracket for the baggage rack.

35 It will be understood that the choice of a particular embodiment of the invention for illustration and description is for the purpose of complying with Sec. 4888 of the Revised Statutes with respect to disclosure, but the appended claims are 40 not to be limited to the construction shown and described, unless the prior art requires that interpretation.

Referring first to Fig. 1, it will be seen that the rack consists of a plurality of rack units 10 (see also Fig. 6), end pieces 11, (see also Fig. 7), and a plurality of intermediate wall brackets, generally designated 12, the latter serving the double function of supporting the rack units 10 and containing lighting fixtures for illuminating 50 the car interior.

The rack units 10 (Fig. 6) comprise a plurality of parallel supports 13, in the present case tubes, the ends of which are rigidly secured to right and left section castings 14 and 15, respectively, 55 which may be called the baggage supporting ele-

ment end pieces. The two castings are similar, and each is provided with a plurality of openings 16 into which the tubes are fitted and held in place by flaring over the ends of the tubes, as shown at 17 in Fig. 3. The castings are provided with a small outwardly extending flange 18 along their bottom, forward and top margins, the flange along the top margin, however, being slightly wider and provided with ears 19 adapted to overlap the wall brackets 12 to enable the 10 unit to be secured to the bracket. Elongated slots 20 in the ears 19 accommodate slight variances in the positioning of the wall bracket, as will be later described in more detail.

The section castings 14 and 15, as well as the 15 tubes, are preferably made of aluminum, although other material may, of course, be used.

The end piece 11 (Fig. 7) consists of an aluminum casting which, in general, has a shape corresponding to the section castings 14 and 15. 20 Assuming that the end piece is for the right end of the rack (as shown in Figs. 2 and 7), it will be seen that the section casting 14 is adapted to interfit with the end piece, with the top and bottom portions of the marginal flange 18 resting 25 upon the top and bottom flanges 21 and 22, respectively, of the end piece, and small cap screws 23 passing through the elongated slots 20 in the section casting 14 and tapped holes 24 in the flange 21, secure the rack unit in place on the 30 end piece.

It will be noticed in Fig. 2 that there is a clearance 25 between the section casting 14 and the end piece 11 which enables slight variances in the 35 positioning of the end piece 11 to be accommodated, and at the same time, the bottom flange 22 of the end piece masks the spacing of the rack unit 10 from the end piece.

The end piece is secured to the car wall by 40 suitable fastening means, as for example, machine screws 26.

The wall brackets 12 each comprise a box housing 27 which extends substantially the full width of the rack, the top of the housing being closed by a cover 28 and the bottom by a light-transmitting wall or bowl 29. The housing is preferably cast in aluminum, and has outwardly extending side ledges 30 upon which the flanges 18 of the adjacent rack units 10 or the downwardly facing surfaces thereof are adapted to rest. 50 (See Fig. 2.) The upper enlarged portion of each end piece 14, 15, or the downwardly facing surface thereof, is adapted to rest upon the top wall of the housing, which constitutes a supporting ledge, with the ears 19 mating with lugs 31 55

formed on the housing or on a transverse member thereof connecting the side walls of the housing. The lugs have tapped holes 32 for receiving cap screws 33 which also pass through the elongated slots 20 in the ears 19 to hold the rack unit 10 in adjusted position on the wall bracket. As in the case of the end piece 11, the ledges 30 on the wall brackets 12 mask the spacing of the rack units 10 from the bracket so that viewed from below, the rack has a neat appearance.

Within the housing 27 are lamp units 34, 35 and 36, the first two being used for ordinary lighting and controlled by a switch 37 and the smaller unit 36 being used as a night light under the control of the car attendant from a remote point. The lamp units 34 and 35 are supported in the housing by angle brackets 38 and 39, respectively, which are secured to one of the side walls of the housing by small nuts and bolts 40. Preferably, the lamp units 34 and 35, are slightly out of axial alignment so as to provide suitable clearance for the lamp unit 36 and allow the bulbs of any one to be removed without interference from either of the other bulbs within the housing.

The bowl 29 is removably secured in the housing and comprises a molded translucent glass dish having slightly flared side walls 41 and end lips 42, the forward one of which is adapted to rest on the floor of the housing 27 (see Fig. 4) (preferably a small gasket 43 is interposed between the lip and the housing) and the other upon a retaining strip 44 which is removably secured to the housing by small screws 45 entering lugs 46 formed on the floor of the housing 27.

In other words, the bowl is assembled with the housing by first inserting the forward edge through the opening in the lower wall of the bracket and allowing the forward lip to rest on the floor of the housing and then the rear portion of the bowl is raised into position and held in place by the retaining strip 44. In order to insure that the bowl 29 will not rattle within the bracket, rubber strips 47 are secured to the inner side walls of the housing by retaining clips 48 held in place by nuts and bolts 49 (Fig. 2) and when the rear end of the bowl is lifted into place for application of the retaining strip 44, the side walls 41 of the bowl make firm engagement with the rubber strips 47 and prevent movement of the bowl relative to the bracket.

A plurality of binding posts 50 are fastened to the rear wall of the housing 27 and a pair of openings 51 on each side of the housing and 55 in axial alignment with the two rear tubes of the rack units (see Figs. 3, 5, and 6) enable the necessary wiring to pass through the rack units obscured from the sight of passengers.

Access to the interior of the bracket is obtained through the cover 28 which is hinged to the housing 27, as indicated at 52, and overlaps the top flange of the adjacent section castings (see Fig. 2). The cover is provided with a closed rubber gasket 53 which, when the cover is secured in place by the thumb screw 54, positively insures that no light will leak out through the housing to cause undesirable lights and shadows.

To increase the effectiveness of the lighting, the cover 28 is equipped with a pair of reflectors 55 suitably spaced from the cover by brackets 56, as best shown in Fig. 4.

From the above description, it will be seen that access to the lighting unit may be obtained by merely unscrewing the thumb screw 54 and opening the cover and that in case the wall

bracket must be removed for repair of the fixtures, the removal may easily be effected by merely taking off the adjacent rack units and then unscrewing the screws 57 which hold the bracket to the wall.

We claim as our invention:

1. In a baggage rack, a pair of adjacent units each comprising a baggage supporting element, an end piece connected to the adjacent ends of said elements, each end piece comprising a substantially vertical wall and including downwardly facing surfaces vertically spaced apart, and a wall bracket including upper ledges overlapped by the upper of said surfaces and lower ledges overlapped by the lower of said surfaces, certain 15 of said ledges supporting said end pieces and each of said lower ledges masking the gap between the adjacent unit and vertical wall.

2. In a baggage rack, a pair of adjacent units each comprising a baggage supporting element, 20 an end piece connected to the adjacent ends of said elements, each end piece comprising a substantially vertical wall and including downwardly facing surfaces vertically spaced apart, a wall bracket including upper ledges overlapped by the 25 upper of said surfaces and lower ledges overlapped by the lower of said surfaces, and means securing the end pieces to said upper ledges, each of said lower ledges masking the gap between the adjacent unit and vertical wall.

3. In a baggage rack, a pair of adjacent units each comprising a baggage supporting element, an end piece connected to the adjacent ends of said elements, each end piece comprising a substantially vertical wall and including downwardly 35 facing surfaces vertically spaced apart, a wall bracket including upper ledges overlapped by the upper of said surfaces and lower ledges overlapped by the lower of said surfaces, and means connecting the end pieces to the upper ledges 40 of the bracket in any of a plurality of adjusted degrees of separation of the end pieces and bracket, said lower ledges masking the gap between the adjacent unit and vertical wall.

4. In a baggage rack, a plurality of units each 45 comprising a baggage supporting element, an end piece connected to each opposite end of each element, and a plurality of wall brackets each including oppositely directed, vertically spaced, upwardly facing ledges extending longitudinally of the bracket and transversely of the rack, each ledge being overlapped by a portion of an end piece whereby each bracket, including certain of its ledges, masks the gap between adjacent units.

5. In a baggage rack, a plurality of units each comprising a baggage supporting element, an end piece connected to each opposite end of each element, a plurality of wall brackets each including oppositely directed, vertically spaced, upwardly facing ledges extending longitudinally of the bracket and transversely of the rack, each ledge being overlapped by a portion of an end piece, whereby the bracket, including the ledges, masks the gap between the end pieces of adjacent units, and means connecting the end pieces to the upper ledges of the brackets in any of a plurality of adjusted degrees of separation of bracket and end piece to compensate for unequal spacing of the brackets.

6. In a baggage rack, a wall bracket comprising a box housing including vertically spaced top and bottom walls, and spaced apart side walls, outwardly directed side ledges carried by the lower portions of the side walls and extending 75

substantially the full length of said walls, and baggage supporting units each including an end piece having a lower surface substantially as long as said ledges, overlying the ledge of one of said side walls and masked thereby, and having a flange outwardly directed from its upper portion overlying and connected to the upper portion of said side wall.

7. In a baggage rack, a wall bracket comprising a box housing including vertically spaced top and bottom walls, and spaced apart side walls, outwardly directed side ledges carried by the lower portions of the side walls and extending substantially the full length of said walls, baggage supporting units each including an end piece having a lower surface substantially as long as said ledges, overlying the ledge of one of said side walls and masked thereby, and having a flange outwardly directed from its upper portion overlying and supported on the upper portion of said side wall, and means connecting said flange and the upper portion of said side wall in any of a plurality of adjusted degrees of separation of the end piece and bracket.

8. In a baggage rack, a wall bracket comprising a box housing including vertically spaced top and bottom walls, spaced apart metal side walls, metal end walls connecting the side walls and preventing separation thereof, outwardly directed side ledges carried by the lower portions of the side walls and extending substantially the full length of said walls, and baggage supporting units each including an end piece of substantially the same width as said side walls, mounted adjacent one of said side walls, and having a lower surface substantially as long as said ledges, overlapping the ledge of said side wall and masked thereby.

9. In a baggage rack, a plurality of wall bracket elements each comprising a hollow box housing having means at one end for connecting the bracket to a wall and having relatively deep horizontally spaced side wall members and

a transverse member connecting the side wall members and holding the same in spaced relation, baggage rack elements supported on the bracket on opposite sides thereof, and means securing the baggage rack elements to the bracket elements in any of the plurality of degrees of separation of adjacent brackets, said securing means being positioned above a portion of the bracket whereby said portion of the bracket conceals the securing means from the view of a person below the level of the rack, and each securing means comprising a part movable with relation to at least one of said elements.

10. In a baggage rack, a plurality of wall brackets each comprising a member having a substantially horizontal surface normally concealed from view from below the rack, baggage rack units supported on the bracket on opposite sides thereof, and means securing the units to the bracket in any of a plurality of degrees of separation of adjacent brackets, said securing means comprising an adjustable pin and slot device, one part of said device being carried by the named surface of the bracket and the other part being carried by the adjacent unit.

11. In a baggage rack, a plurality of wall brackets each comprising a member having a substantially horizontal surface normally concealed from view from below the rack, baggage rack units supported on the bracket on opposite sides thereof, means securing the units to the bracket in any of a plurality of degrees of separation of adjacent brackets, said securing means comprising an adjustable pin and slot device, one part of said device being carried by the named surface of the bracket and the other part being carried by the adjacent unit, and means for locking the pin and slot device in adjusted position.

CARL H. LARSON.
